(57) **CLAIM**

The ornamental design for a vaginal ring applicator, as shown and described.

DESCRIPTION

A portion of the disclosure of this patent document contains material which may be protected by copyright. The copyright owner has no objection to the facsimile reproduction by any one of the patent document or the patent disclosure, as it appears in the Patent and Trademark Office patent file or records, but reserves all other copyright rights whatsoever.

FIG. 1 is an exploded top perspective (plunger, barrel, right) view of a vaginal ring applicator;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view of the combined vaginal ring applicator; and,

FIG. 10 is cross section view thereof taken along lines 10-10 in FIG. 9.

The broken lines shown in the figures represent portions of the vaginal ring applicator that form no part of the claimed design.
